UNITED STATES PATENT OFFICE.

NORMAN G. MEADE, OF WILKINSBURG, PENNSYLVANIA, ASSIGNOR OF ONE-HALF TO
JOHN B. COMSTOCK, OF EDGEWOOD PARK, PENNSYLVANIA.

AUTOMATIC PLAYER FOR MUSICAL INSTRUMENTS.

1,006,669.

Specification of Letters Patent.

Patented Oct. 24, 1911.

Application filed March 25, 1907. Serial No. 364,531.

To all whom it may concern:

Be it known that I, NORMAN G. MEADE, a citizen of the United States, and a resident of Wilkinsburg, in the county of Allegheny and State of Pennsylvania, have invented a new and useful Improvement in Automatic Players for Musical Instruments, of which the following is a specification.

My invention relates to devices for the automatic production of music and has special reference to automatic players for pianos and like instruments.

The object of my invention is to provide a device of the class above indicated that shall be simple and durable in construction and that shall embody improved means for automatically regulating the tempo, touch and pedals of the instrument with which it is connected.

Automatic piano players have usually comprised means for operating the piano keys by strikers or hammers, such means being governed by a sheet of perforated paper that was passed gradually over a set of holes in the wall of a pneumatic chamber.

According to my present invention, I provide a chamber or hollow cylinder having a series of holes in one wall, means for exhausting the air from the chamber, a series 30 of spring contact members, and pins which are fitted loosely into the holes in the chamber wall and which are adapted to effect the closure of electric circuits through one or more of the spring contact members when 35 air or other fluid-pressure is applied to their outer extremities. These contact members correspond in number and relative location to the keys of a piano and several additional contact devices are provided which are 40 adapted to effect the automatic control of the tempo or rate of playing, the operation of the pedals, and the touch, or the force with which the playing hammers or strikers are actuated. The admission of air-pressure 45 to the chamber is dependent upon a plurality of perforations or holes through a sheet or strip of suitable material, such as paper, which is passed over the chamber, preferably from one roll to another, in a well-known manner, and additional perforations, 50 as hereinafter explained, are provided for the control of expression.

My invention is illustrated in the accompanying drawings, in which—

Figure 1 is a plan view of an automatic 55 piano player constructed in accordance therewith. Fig. 2 is a side elevation, Figs. 3 and 4 end elevations, and Figs. 5, 6, 7 and 8 detail views of the device shown in Fig. 1. Fig. 9 is a diagrammatic view of 60 the action and circuit connections for a piano and my improved playing device.

Referring to Figs. 1 to 8, inclusive, of the drawings, the device illustrated comprises a stationary base 1, a vacuum chamber 2, 65 and rolls 3 and 4 which are supported upon the base 1 by a frame 5. This frame consists of two end brackets or plates 6 and 7 that are bolted to the base, and tie-bolts 8 that interconnect the end brackets. The air 70 is exhausted from the chamber 2 by means of pumps 9 and 10 which comprise oscillating cylinders and pistons and which are driven by an electric motor 11, through a train of gears, a shaft 12 and eccentric projections 75 13. The pumps 9 and 10 may be replaced by a well-known type of centrifugal pump or by any other suitable device for exhausting the air from the cylinder.

A main driving shaft 14 of the mechanism is rotatably mounted in stationary bearings 15 and is connected to the shaft of the motor 11 by a pinion 16 on the motor shaft, a gear wheel 17 and a pinion 18 on a jack shaft 19, and a gear wheel 20 which is fixed to the shaft 14 and meshes with the pinion 18, the pinion 16 meshing with the gear 17 on the jack shaft. The pump shaft 12 is driven from this main shaft by sprocket wheels 21 and 22 that are connected 80 by a chain 23 and by gear wheels 24 and 25, the sprocket wheel 22 and the gear wheel 25 being keyed to a rotatable jack shaft 26.

The rolls 3 and 4 are rotatably mounted upon shaft projections between the end 95 brackets 6 and 7, and spur gear wheels 28 and 29 are attached to corresponding ends of the rolls 3 and 4 on the extremities of the shaft projections which extend through the end frames 6 and 7. A beveled gear 100 wheel 30 is attached to the opposite shaft projection from the roll 4. The longitudinal axes of the chamber 2 and the rolls 3 and 4 are substantially parallel. One of

the outer surfaces of the chamber is of cylindrical curvature and the position of the rolls is such that when a film or strip 30^a is wound over the roll 3, across the cylindrically curved surface of the chamber 2, and onto the roll 4, a slight downward pressure is exerted against the engaged surface of the chamber. A screw-threaded rod 31 is rotatably mounted in brackets 32 that are attached to the end plate 6 and the rotation of this rod is effected through a beveled gear wheel 33 which meshes with the beveled gear wheel 30.

Between the end bracket 7 and the corresponding stationary bearing 15, a bell-crank lever 33^a is pivotally mounted upon the shaft 14. The bell-crank lever comprises two arms 34 and 35 substantially at right angles to each other near the extremities of which sheaves 36 and 37, a spur gear wheel 38, a sheave 39 and a spur gear wheel 40 are rotatably mounted. The sheaves 37 and 39 are connected by a belt 41 or other driving connection, and the sheave 36 is connected to a sheave 42 with which the shaft 14 is provided, by means of a crossed belt 43. The sheaves 36 and 37 and gear wheel 38 are attached to the same shaft, so that their angular velocity is always the same. This is also true of the sheaves 39 and the gear wheel 40. The rotation of the bell-crank lever on the shaft 14 is limited in one direction by a stop 44 which is attached to the end bracket 7, and it is constrained to occupy this extreme position in which the gear wheel 38 meshes with the gear wheel 29 of the roll 4 by a helical spring 45. The jack shaft 26 is affixed to the outer extremity of a lever 26^a which is fulcrumed at an intermediate point 26^b and has a slot and pin connection at its inner extremity with the arm 35 of the bell-crank lever 33^a. The arrangement of parts is such that the gear wheel 25 meshes with the gear wheel 24 only when the arm 35 engages the stop 44.

An actuating electro-magnet 46, having windings 47 and an armature 48 that is pivoted upon a pin 49, is attached to the stationary bracket 7, and this armature is connected to the outer extremity of the arm 34 of the bell-crank lever 33^a, by means of a link 50. When the electro-magnet is energized, its armature is rotated through a slight angle about its axis and, in consequence of this movement, the bell-crank lever is rotated in opposition to the spring 45 until the gear wheels 38 and 25 are respectively disengaged from the gears 29 and 24 and the gear wheel 40 moves into engagement with the gear wheel 28. When the bell-crank lever occupies one position, the take up roll, onto which the music strip is wound, is rotated in one direction and 65 the other roll is free to follow. On the

other hand, when the bell-crank lever occupies its opposite position, rotation of the roll on which the music strip was originally wound is effected in a reverse direction and the take up roll is free. The function of 70 this portion of the mechanism will be more specifically pointed out hereinafter.

A motor-starting switch 51 is attached to the end bracket 6 and comprises a movable contact member 52, stationary contact members 53 and 54, stops 55, which limit the movements of the member 52, and a spring 56 that tends to keep the movable contact member in its open-circuit position. The switch 51 is adapted to be closed 80 by the movable member 58 of a switch 57 that closes the circuit of the magnet windings 47 of the electro-magnet 46 when said movable contact arm is moved to engage stationary contact members 59. The arrangement of parts is such that when the switch 51 occupies its open circuit position, the switch 57 also occupies its open circuit position, but when the motor circuit is complete, the switch 57 may be closed by energizing an actuating magnet 60, having a winding 61 and a movable armature 62 that is connected to the movable arm 58 by means of a link 63. In starting the motor, the switch 51 may be manually closed by 90 means of an actuating rod 64 that does not interfere with the free operation of the switch under normal conditions by reason of a spring 65 which holds the adjacent end of the rod out of range of the switch. 100

The chamber 2 may preferably be constructed as illustrated in Fig. 6, which is a sectional elevation of this portion of the device, the upper cylindrical surface being provided with a plurality of grooves or saw cuts 105 66 in order to direct the air into the holes 67, which may be somewhat irregularly located. A smooth contact surface, over which the music strip 30^a may pass, is provided by a sheet metal plate 68 that is bent 110 to conform in shape to the surface of the chamber and is provided with a series of slots or openings 69 through which air may be admitted to the slots 66, when perforations in the music strip coincide with these 115 holes in the plate. The sheet metal plate 68 and the slots 66 may be omitted if the holes 67 are regularly located and are provided with sharp edges so that their coincidence with the holes in the music strip may 120 be well defined. A comb or notched strip 70, of conducting material, is supported upon a ledge 71 in the chamber 2 and extends substantially throughout its length. The projections or teeth of the comb 70 125 form independent, resilient fingers a, b, c, d, e, f, g, h and i which may be moved into engagement with stationary contact points 72 by pins 73 that are fitted loosely into the holes 67 and rest upon the contact fingers, 13

when fluid-pressure is exerted upon the upper ends of the pins. The air-pressure is obtained from the outside atmosphere by producing a partial vacuum in the chamber 2 by means of the exhaust pumps 9 and 10.

As illustrated in Figs. 7, 8 and 9 each of the keys of the piano is equipped with an electro-magnet 73^a that comprises a core member 74 forming a substantially closed magnetic circuit of rectangular shape and a magnet winding 75 which encircles one leg of the core. The core member 74 is provided with a magnetizable strip 76 that is 15 rotatably attached to the core proper and is adapted to completely close the magnetic circuit when a magnetic field is produced by energizing the windings 75. This movable member is mechanically connected to one of 20 the piano keys 77 by means of a wire or strip 78, the lower extremity of which is hooked into engagement with an eyelet 79 that is attached to the piano key. The desired result may obviously be obtained with 25 equal facility, whether the magnet is located above the key and its movable member is connected to it at a point between its fulcrum and its inner end, as shown, or whether the magnet is located below the key and its 30 movable member is connected to the key between its fulcrum and its outer end. The position of the magnets will, of course, be determined by the style of instrument to which the player is attached. The space occupied by one of the electro-magnets 73^a is 35 materially greater than the width of a single key plus the distance between adjacent keys, and, consequently, adjacent electro-magnets are staggered in a well-known 40 manner.

In obtaining the expression, particularly variations in the tempo and touch, a device similar to that illustrated in Fig. 5 may advantageously be employed. This device 45 comprises a plurality of stationary contact ring segments 80 which are fixed to an insulating plate or slab 81, a rotatable engaging contact arm 82, a ratchet wheel 83 fixed thereto, an electro-magnet 84 having a winding 85 and a pivotally mounted armature 86, and a pawl 87 which is pivotally attached 50 to the outer extremity of the armature 86 and is held in engagement with the ratchet wheel 83 by means of a spring 88.

Assuming that a music strip is wound on 55 the roll 3 and that its loose end is passed over the curved surface of the chamber 2 formed by the plate 68 and is attached to the roll 4, the electric motor 11 may be 60 started by manually actuating the rod 64 to close the switch 51.

The motor 11 may be of any suitable type having a variable speed characteristic and may be supplied with energy from any suitable source. The circuit connections for the 65

motor, which, as illustrated in Fig. 9, is a compound wound motor of the direct current type, may be traced as follows: Energy is supplied from a relatively high voltage source of electrical energy, such as a shunt generator 89, through a variable resistance 90 and switch 51 to the motor 11. The variable resistance 90 is intended to effect a speed regulation of the motor rather than to serve as a starting rheostat, and in case an 70 alternating current motor is employed for driving the device, this resistance can be replaced by an auto-transformer or other suitable means for varying the voltage applied to the motor circuit. As illustrated, 75 the resistance 90 is controlled by a device, such as that shown on a larger scale in Fig. 5, and, under normal conditions, the movable contact arm occupies a position such that approximately half of the resistance is 80 included in the motor circuit and, therefore, a speed variation is permitted in either direction. A reasonable amount of the music strip may preferably be left without perforations, so that the motor may have an 85 opportunity to accelerate, and, when normal conditions obtain, the music strip will be traveling over the holes 69 in the plate 68 at a substantially constant speed. As predetermined perforations in the sheet pass 90 over the holes corresponding to the desired keys, certain of the pins 73 are given a downward motion so that the corresponding contact fingers engage the stationary contact terminals 72. A circuit is now completed 95 through any convenient source, such as a storage battery 91, illustrated in Fig. 9, to the comb or notched strip 70, through stationary contact terminals 72, and conductors 92, to magnet windings 75 of the electro-magnets 73^a, the circuits being completed from these points through a single resistance 93 to the negative terminal of the battery. The resistance 93 is representative of any suitable voltage-varying means and may be 100 mechanically arranged, as the device shown in Fig. 5. In this case, as before, under normal conditions, the movable contact arm occupies such a position that approximately one half the resistance is included in the circuit. 105

Inasmuch as the function of the pedals in a piano is well known, I deem it unnecessary to describe their action here, but in my automatic device, these parts are actuated, as 110 illustrated in Fig. 9, by means of electro-magnets 94, 95 and 96. These magnets are provided with windings 97, 98 and 99 and movable core members 100, 101, and 102 that are severally connected to the pedal-actuating rods by means of links 103. The magnet windings 97, 98 and 99 may be energized selectively by the closure of control switches 104, 105 and 106. These switches are electrically operated, being equipped with mag- 115

net windings 107, 108 and 109, which, in turn, may be energized when contact fingers *d*, *e* and *f* are moved into engagement with their co-operating stationary contact terminals 72. It will be readily understood that the desired pedal action may be effected by providing suitable perforations in the music strip 30^a for selectively applying air-pressure to the pins 73 that correspond to the contact fingers.

The regulation of the tempo is effected by increasing and decreasing the active portion of the resistance 90, and the touch or the force with which the hammers or strikers are actuated may be varied by decreasing or increasing the active portions of the resistance 93. The regulation of the resistance 90 and the regulation of the resistance 93 are respectively dependent upon the actuation of the contact fingers *h* and *g* and are similarly effected, so only one will be described in detail, reference being had to Fig. 5 in connection with the diagram of Fig. 9. The magnet winding 85 is energized directly from the battery 91 when contact finger *h* moves into engagement with its stationary contact terminal 72, and the resulting motion of the armature 86 effects the rotation of the contact arm 82 from one of the contact ring segments 80 to the next adjacent segment by reason of the engagement of the pawl 87 with the ratchet wheel 83, the number of teeth on the ratchet wheel corresponding to the number of ring segments. It will be readily understood that, with the arrangement shown, rotation of the movable contact arm can only be effected in one direction, but, by providing a series of perforations in the music strip, the contact arm may be moved from one ring segment to any other desired ring segment so quickly that no perceptibly undesirable effect on the music will result. For example, a single perforation will, of course, move the arm in a clockwise direction from one ring segment to the next adjacent ring segment, and on the other hand, five perforations, close together, in a direct line, on the music sheet will virtually effect a counter-clockwise movement from any one contact ring segment to the next adjacent contact ring-segment.

When the music strip has been wound onto the roll 4 until all the music-producing perforations have passed the holes 69 in the plate 68, a single perforation is provided for actuating a spring contact member *i* which completes a circuit through the magnet winding 61 of the magnet 60 to close the switch 57. The closure of this switch energizes the magnet windings 47 of the electro-magnet 46 from the main source of energy. As soon as this magnet is energized, the bell-crank lever 33^a is rotated through a small angle in opposition to the spring 45 until the

gear wheels 38 and 25 become disengaged from the gear wheels 29 and 24, and the gear wheel 40 moves into engagement with the gear wheel 28. As soon as these conditions obtain, the roll 3 is rotated in a reverse direction from its normal playing motion and, consequently, the music strip is rewound upon the roll 3. A repetition of the musical notes in a reverse order is prevented by the equalization of the air-pressure within and without the chamber 2 which follows the disengagement of the gear wheel 25 from the gear wheel 24 and the stopping of the exhaust pumps.

The screw-threaded rod 31, which is driven from the roll 4, is provided with a travelling nut 112, which is provided with a pawl projection 113 to engage the arm 52 of the switch 51 and move it slightly in order that the spring 56 may move it to its open-circuit position when the music strip has been entirely rewound upon the roll 3. In this way, the motor is employed for rewinding the music strip onto the original roll, and, after this action is complete, the motor circuit is interrupted. A slight movement of the arm 52 by the projection 113 is sufficient to enable the spring 56 to separate the contact member 53 from the terminal 54, and, thereupon, the nut 112 immediately stops in such position as to permit the rod 64 to engage the arm 52 and move it to its circuit-closing position when desired.

I claim as my invention:

1. In an automatic musical instrument, the combination with a pneumatic chamber having a set of holes through one wall, a roll or cylinder rotatably mounted at each side of the chamber, and a perforated strip or film wound on one roll, of a pump for exhausting the air from the chamber, a motor for driving both the pump and the rolls, and means dependent upon predetermined perforations in said strip or film for reversing the rolls and for disconnecting the pump from the motor.

2. In an automatic musical instrument, the combination with a pneumatic chamber having a set of holes through one wall, a roll or cylinder rotatably mounted at each side of the chamber, and a perforated strip or film wound on one roll, of a pump for exhausting the air from the chamber, a motor for driving both the pump and the rolls to wind the film from one roll to the other, means for reversing the rolls to rewind the strip and for disconnecting the pump from the motor, and means for automatically bringing the motor to rest when the rewinding operation is completed.

3. In an automatic musical instrument, the combination with a pneumatic chamber having a set of holes through one wall, a roll or cylinder rotatably mounted at each side of the chamber and a perforated strip or

film wound on one roll, of a pump for exhausting the air from the chamber, a motor for driving both the pump and the rolls, and an electro-responsive device for reversing the rolls and for disconnecting the exhaust pump from the motor.

4. In an automatic musical instrument, the combination with a pneumatic chamber having a set of holes through one wall, 10 spring contact fingers disposed in the chamber, actuating pins that engage the fingers and project loosely into the holes in the chamber wall, a roll or cylinder rotatably mounted at each side of the chamber, a perforated strip or film wound on one roll, an exhaust pump for the chamber, and an electric motor for driving the pump and for transferring the strip or film from one roll 15 to the other and over the holes in the chamber, of an electro-responsive device for reversing the rolls and for disconnecting the exhaust pump from the motor, an electrically-operated circuit interrupter for the

motor, and means dependent upon the opening of the motor circuit for deenergizing the 25 electro-responsive device.

5. In an automatic musical instrument, the combination with a pneumatic chamber having a set of holes in one wall, a roll mounted at each side of the chamber, pumps 30 for exhausting the air from the chamber, and a motor for driving the pumps and for actuating the rolls in one direction, of a perforated strip or film wound on the rolls and stretched over the holes in the chamber, 35 and means controlled by the strip or film to automatically reverse the rolls and stop the pumps and to finally interrupt the motor circuit.

In testimony whereof, I have hereunto 40 subscribed my name this 18th day of March, 1907.

NORMAN G. MEADE.
